UNITED STATES PATENT OFFICE.

THOMAS W. MORGAN, OF WATERLOO, IOWA, ASSIGNOR TO WILBUR W. MARSH, OF WATERLOO, IOWA.

DRIVING MECHANISM FOR CENTRIFUGAL SEPARATORS.

No. 847,802.

Specification of Letters Patent.

Patented March 19, 1907.

Application filed January 26, 1906. Serial No. 297,943.

To all whom it may concern:

Be it known that I, THOMAS W. MORGAN, a citizen of the United States of America, and a resident of Waterloo, Blackhawk county, Iowa, have invented certain new and useful Improvements in Driving Mechanism for Centrifugal Separators, of which the following is a specification.

My invention relates to improvements in driving mechanism for centrifugal separators; and the object of my invention is to provide a ratchet device to be inserted in such a manner within the mechanism of the driving means of a centrifugal separator whereby the driving-gear may be disconnected from the driven gear thereof. This object I have effected by the mechanism which is hereinafter described and claimed and which is illustrated in the drawing hereto annexed, in which—

Figure 1 is a view in perspective of an elevation of the centrifugal separator, the casing thereof being shown in partial section; and Fig. 2 is a detail view showing my improved ratchet device, parts being shown in section. Fig. 3 is an enlarged detail view of the detent-bearing nut and pinion, and Fig. 4 is an end elevation of the same.

Similar letters refer to similar parts throughout the several views.

I have shown in Fig. 1 the driving mechanism of a centrifugal separator of a well-known type arranged to rotate a bowl for separating cream from the other constituents of milk. The upper cylindrical portion *t* of the casing *p* contains a collar-bearing *x* for the reception of the spindle *j* of the separator-bowl *w*. The lower half of the casing *p* is formed in the shape of a truncated cone 40 with its upper truncated edge united to the lower edge of the cylindrical portion *t*, and a bearing *q*, having the same axis as the axis of the bearing *x*, being fixed at this point of junction. A base-plate *z* extends across the lower end of the hollow conical casing *p* and supports a step-bearing *m*, having the same axis as the other bearings. A vertical shaft *l* has its lower end inserted in the step-bearing *m*, while its upper end projects through 45 the intermediate bearing *q* and is provided with a horizontally-extending stud *r*, arranged to engage with the sides of a slot in the lower end of the spindle *j*. The shaft *l* bears a spiral gear *k*, which intermeshes with

the spiral pinion *n*, mounted on a shaft *a*, set 55 transversely in bearings (not here shown) in the casing *p*. The shaft *a* has a fixed collar *b* to prevent movement in one direction of the split spring-washer *c*, the latter being slipped over the diminished portion *i* of said shaft, 60 the latter serving to keep the washer in place. The gear-wheel *e* is rotatably mounted on that portion of the shaft *a* which extends beyond the washer *c*, a coil-spring *d* being inserted around said shaft between the 65 said washer and the said gear-wheel *e*. The rotatable gear *e* bears a detent *f*, which engages a detent *g* on the nut *h* when the former is rotated in one direction. The nut *h* is fitted on the threaded end of the shaft *a*. 70 The gear-wheel *e* intermeshes with the gear-wheel *o*, the latter being mounted on a shaft *s*, set in a transverse bearing *u*, affixed to the upper cylindrical part *t* of the separator-casing. The other end of the shaft *s* is provided 75 with a crank *v*, having a handle *y*.

When the gear-wheel *o* is rotated in one direction, the detent *f* on the gear-wheel *e* is caused by the spring *d* to engage with the detent *g* on the nut *h*, setting the shaft *a*, with 80 its spiral pinion *n*, the spiral gear *k*, shaft *l*, and spindle *j*, in rotation. When it is desired to disconnect the crank *v* and driving gear-wheels *o* and *e* from the driven mechanism, the handle *y* is simply held in one position, when the driven parts will gradually come to a stop, the detents gliding over each other. A great deal of wear on the driving parts is thus prevented and the driving mechanism more quickly brought to a stand- 90 still.

Having described my invention, what I claim as new, and desire to secure by Letters Patent, is—

1. In a driving mechanism, the combination of a partially-threaded shaft *a* a detent-bearing nut removably mounted on the threaded end of said shaft, a pinion mounted loosely on the said shaft and provided with a detent, and a spur-wheel adapted to engage 95 with the said pinion, and means for causing the detent on said pinion to engage with the detent on said nut when said pinion is rotated in one direction.

2. In a driving mechanism, the combination of a shaft threaded at one end, a detent-bearing nut removably mounted on the threaded end of said shaft, a pinion mounted 105

loosely on the said shaft and provided with a
detent, a spur-wheel adapted to engage with
the said pinion, a collar on said shaft, and a
spring seated around said shaft between said
collar and said pinion and adapted to cause
the detent on said pinion to engage the detent
on said nut when said pinion is rotated in one
direction.

3. In a driving mechanism, the combina-
10 tion of a grooved shaft threaded at one end, a
detent-bearing nut removably mounted on
the threaded end of said shaft, a pinion
mounted loosely on the said shaft and pro-
vided with a detent, a spur-wheel adapted to
15 engage with the said pinion, a collar on said
shaft, a split washer mounted in the groove
of said shaft, and a spring seated around said
shaft between said collar and said pinion and
adapted to cause the detent on said pinion to
20 engage with the detent on said nut when said
pinion is rotated in one direction.

4. In a driving mechanism for centrifugal
separators, a combination of a shaft threaded
at one end, a detent-bearing nut removably
25 mounted on the threaded end of said shaft, a
pinion mounted loosely on the said shaft and
provided with a detent, a spur-wheel adapted
to engage with the said ratchet, means for
causing the detent on said pinion to engage
30 with the detent on said nut when said pinion
is rotated in one direction, a spiral-gear wheel
mounted fast on said shaft, a vertical shaft
and a spiral pinion mounted fast on said ver-
tical shaft and adapted to engage with said
35 spiral-gear wheel.

5. In a driving mechanism for centrifugal
separators, the combination of a shaft

threaded at one end, a detent-bearing nut re-
movably mounted on the threaded end of said
shaft, a pinion mounted loosely on said shaft
and provided with a detent, a spur-wheel
adapted to engage with the said pinion, a col-
lar on said shaft, a spring seated around said
shaft between said collar and said ratchet, and
adapted to cause the detent on said pinion to
45 engage with the detent on said nut when said
pinion is rotated in one direction, a spiral-
gear wheel mounted fast on said shaft, a ver-
tical shaft, and a spiral pinion mounted fast
on said vertical shaft and adapted to engage
50 with said spiral-gear wheel.

6. In a driving mechanism for centrifugal
separators, a combination of a grooved shaft
threaded at one end, a detent-bearing nut re-
movably mounted on the threaded end of 55
said shaft, a pinion mounted loosely on said
shaft, and provided with a detent, a spur-
wheel adapted to engage with the said pinion,
a collar on said shaft, a split washer mounted
in the groove in said shaft, a spring seated
60 around said shaft between said washer and
said pinion and adapted to cause the detent
on said pinion to engage with the detent on
said nut when said pinion is rotated in one di-
rection, a spiral-gear wheel mounted fast on
65 said shaft, a vertical shaft, and a spiral pin-
ion mounted fast on said vertical shaft and
adapted to engage with said spiral-gearwheel.

Signed at Waterloo, Iowa, this 5th day of
January, 1906.

THOMAS W. MORGAN.
